FLIP-OUT DEVICE FOR FUSES

Chester W. Brown, Milwaukee, Wis., assignor to
 Line Material Company, Milwaukee, Wis., a corporation of Delaware

Application August 15, 1942, Serial No. 454,924

14 Claims. (Cl. 200—127)

This invention pertains to fuse cut-outs and has to do more especially with a device commonly known as a "flip-out" which is operative, immediately after the blowing of a fuse and in response thereto, quickly to separate the arc electrodes within the fuse cartridge and, preferably, to wholly expel from the open end of the cartridge the elongate conductive leader constituting a severed part of the fuse link.

The purpose underlying the use of such devices is to ensure extinguishment of the arc within the fuse cartridge when the blow-out is caused by a fault current of such little amperage that the ensuing explosion is not amply forceful to expel the leader or to bring about a sufficient separation of the arc electrodes within the cartridge.

Modern dropout fuses are furnished factory-equipped with flip-outs which function as above indicated; and the same is true with respect to some fuse cut-outs of the non-dropout type. But there are in use a great many fuse cut-outs of the simple expulsion non-dropout type which are not equipped with in-built flip-outs, and it is to the equipping of the latter that the present invention is more particularly addressed.

The primary object of the present invention is to provide an inexpensive flip-out which can be utilized as an accessory to an expulsion fuse cut-out not otherwise so equipped.

Another and related object is to provide an accessory of the aforementioned character which can easily and quickly be installed in the field.

Still another object is to provide a simple flip-out which is inherently operative, when properly installed, to apply a uniform predetermined tension to the fuse-link—which tension is determined at the factory and not dependent upon the lineman's judgment.

The unique features which characterize this invention can most readily be adduced in conjunction with the detailed description of the two preferred embodiments illustrated in the accompanying drawings, wherein:

Fig. 1 is a longitudinal sectional view of one form of flip-out device constituting a preferred embodiment of the invention.

Fig. 2 is a longitudinal sectional view of a fuse cartridge of the expulsion type shown equipped with the flip-out device of Fig. 1.

Fig. 3 is an elevational view, partly in section, of the lower end of the fuse cartridge of Fig. 2, illustrating the manner of operation of the flip-out device of Fig. 1 in response to blowing of the fuse.

Fig. 4 is a longitudinal sectional view of an alternative flip-out device representing a second preferred embodiment of the invention.

Fig. 5 is a longitudinal sectional view of a fuse cartridge of the expulsion type, showing the flip-out device of Fig. 4 being inserted.

Fig. 6 is an elevational view, partly in section, of the lower end of the fuse cartridge of Fig. 5, illustrating the flip-out device of Fig. 4 installed and ready to operate when the fuse blows.

I shall describe first the showing of Figs. 1, 2, and 3 and thereafter the showing of Figs. 4, 5, and 6.

The expulsion fuse cartridge of Figs. 2 and 3 includes an elongate tube 10 which may be of horn fiber or Bakelite lined with fiber or otherwise in accordance with well-known practices. Tube 10 has a bore 10' and is threaded externally at its upper end to accommodate a tubular metal ferrule 11, which is threaded at 12 to receive a removable metal cap 13.

Gripped between cap 13 and the top of ferrule 11 is a button-head contact member 14 which forms an integral part of the upper terminal 15 of a conventional strain-type fuse-link 16. The fuse-link includes a fusible section 17, connected at its upper end to upper terminal 15 and at its lower end to a long flexible conductive leader 18 which extends downwardly through bore 10' and upwardly from the bottom end of tube 10 to a binding-post terminal 19, which includes a metal sleeve 20 and clamping screw 21. Sleeve 20 embraces tube 10 and is secured thereto by a pin 22.

35 The flip-out device, identified as a whole by reference numeral 23, is shown, in Fig. 2, installed in the fuse tube and is separately illustrated in Fig. 1. It comprises an elongate flexible shaft 24 consisting of a close-wound wire

40 helix, an adapter 25 threaded to the upper end of the flexible shaft, a helical spring 26 telescopically surrounding and co-axial with the flexible shaft and secured at its upper end to the adapter, a disc-like nut 27 threaded to the lower end of the spring, and a second disc-like nut 28 threaded to the lower end of the flexible shaft. The inside diameter of flexible shaft 24

45 is such as to fit freely or, in any event, to permit insertion therethrough of flexible leader 18. It is not necessarily a close fit for the leader although it is so illustrated in Fig. 2. The outside diameter of adapter 25 should, preferably, be a free running fit in the fuse tube, but it may be a loose fit or no fit at all, so long as it clears

50 the bore.

To install the flip-out the flexible leader is threaded through the bore of the flexible shaft and the latter, together with the adapter and attached spring 26 is inserted in the open end of the fuse tube; and the spring is stretched and thus put under tension by pushing on the exposed end of the flexible shaft and on nut 28. This results in seating nut 27 against the end of the fuse tube, with nut 28 bearing against nut 27—all as clearly illustrated in Fig. 2. The flexible leader, being pulled taut, is secured at its free end to terminal 19 and it serves to anchor the flip-out in place and to retain it under tension as will be evident from an inspection of Fig. 2.

The flexible shaft, while capable of being easily flexed in response to a laterally applied force, has the inherent property of being very resistant to buckling when operating as a column. For that reason the shaft will always remain erect against the tension of spring 26.

The tension of spring 26 is applied through the flexible shaft and nut 28 to flexible leader 18 and thus normally maintains the fuse-link under considerable tension—which tension is of definite amount, predetermined at the factory and governable by appropriate selection of spring 26 or by appropriately varying the length of the flexible shaft, or both.

When fusible section 17 blows, the flexible leader is no longer capable of restraining the flip-out and, in consequence, the leader is quickly expelled from the fuse tube by the downward movement of the flexible shaft and nut 28—which, of course, is brought about by the contraction of spring 26.

If flexible shaft 24 were not laterally yieldable it is not improbable that the flip-out would be arrested in its action by the flexible leader—due to the abrupt bend in the leader where it emerges from the fuse tube and turns upwardly. But the shaft being quite flexible in response to laterally directed force is capable of bending in the manner illustrated in Fig. 3 whereby to permit the inside end of the leader to move down instantly without hindrance. Thus a quick separation is effected between the arcing electrodes within the cartridge and the arc is quickly extinguished, regardless of whether or not the accompanying explosion is sufficiently forceful to accomplish the same end without the aid of the flip-out.

That part of the flip-out device which in Fig. 3 is shown still within the fuse tube either drops out by gravity or is knocked out by the momentum of the downwardly moving flexible shaft. No doubt both are contributing factors.

In the alternative embodiment of Figs. 4, 5, and 6 the fuse cartridge is identical with that of Fig. 2 and bears the same reference numerals. The flip-out device is shown in detail in Fig. 4 and comprises a tubular metal sleeve 29, a helical spring 30, and a metal ferrule 31. Sleeve 29 is internally threaded at its upper end and thereby secured to the upper end of spring 30. Ferrule 31 is internally threaded to receive the lower end of the spring. Sleeve 29 is frusto-conically flanged at its lower end to form a head 29a which serves to limit the extent to which the sleeve can be inserted into the fuse tube; and ferrule 31 is formed with a frusto-conical skirt designed to fit within the tapered concavity of head 29a, as shown in Fig. 6.

In Fig. 5, sleeve 29 is shown pushed all the way into the fuse tube to the full extent that head 29a 75

will permit; but the spring has not been compressed and, incidentally, ferrule 31 has not been forced into seating engagement with head 29a. Fig. 5, therefore, depicts a condition wherein the flip-out is in process of being installed.

In Fig. 6 ferrule 31 has been pushed up into telescopic engagement with sleeve 29, thereby compressing spring 30; and flexible leader 18 has been pulled taut and anchored to terminal 19. When so anchored, the leader functions to hold spring 30 under compression.

The curled peripheral edge on head 29a provides a suitable surface about which to bend, without crimping, the flexible leader, and the frusto-conically flared skirt on ferrule 31 affords an angular surface over which the flexible leader can slide, and it avoids sharp turns which might tend to impede rapid movement of the spring and ferrule along the leader when a blowout occurs.

It will be apparent that the flip-out of Figs. 4, 5, and 6 operates according to the same principle as that of Figs. 1, 2, and 3 previously described. But here it is the spring rather than its companion member that is first ejected when a blow-out occurs.

The flip-out of Figs. 4, 5, and 6 comprises fewer parts than that of Figs. 1, 2, and 3; but, on the other hand, sleeve 29 entails more costly tooling than any of the parts of the first-described device.

It will be self-evident that each of the two above-described flip-out devices can easily be installed by a lineman in the field, and that each is quite inexpensive to manufacture and, therefore, can be replaced at trifling cost if lost as a result of a fuse blowout. Moreover, it will be apparent that the tension applied to the fuse-link by the flip-out is determined independently of the lineman's judgment—it being essential only that the device be correctly installed, which does not entail the exercise of discretionary judgment on the lineman's part. The tension can be determined at the factory consonantly with the rating of the fuse-link, and flip-outs of different tensions can, if desired, be furnished to suit the various fuse-link sizes.

What is claimed is:

1. A flip-out device comprising, in combination: a helical compression spring, a rigid, tubular sleeve telescopically encircling and co-axial with said spring, one end only of said sleeve being frusto-conically flanged exteriorly, the peripheral edge of the flange being curled to form a curved surface, the other end of said sleeve being secured to the adjacent end only of said spring, and a frusto-conically flanged ferrule connected to the other end of said spring and co-axial therewith, said ferrule being operative to seat within the frusto-conical concavity of said flange when said spring is compressed and thereby to limit the deflection of said spring compressively.

2. A fuse link flipout device for use in an expulsion type fuse tube, said device comprising outer and inner telescopically related tubular members, one end of said outer member being anchored to the corresponding end of said inner member, the opposite ends of said members being free for relative axial movement, at least one of said members including a spring and being expansible axially of the other member, said other member being undeformable lengthwise as a result of stressing of said spring including member axially, the inner of said members providing an

axial bore therethrough and the outer of said members having anchoring means at its free end.

3. A fuse link flipout device for use in an expulsion type fuse tube, said device comprising a tubular member and a helical spring member coaxially and telescopically related, one end of said tubular member being anchored to a corresponding end of said spring member, the opposite ends of said members being free for relative axial movement, said spring member being deformable axially and thus effective to apply lengthwise stress to said tubular member, one of said members being provided with an axial bore therethrough and the other member having anchoring means at its free end.

4. A fuse link flipout device for use in an expulsion type fuse tube, said device comprising a tubular elongated flexible shaft, a helical spring telescopically and coaxially related to said shaft, one end of said shaft being connected to a corresponding end of said spring, the opposite ends of said shaft and spring being free for relative movement axially of said shaft, and anchoring means on the free end of said spring.

5. A fuse link flipout device for use in an expulsion type fuse tubes, said device comprising a tubular elongated flexible shaft consisting of a close-wound wire helix, a helical spring telescopically related to and encircling said shaft, one end of said shaft being connected with a corresponding end of said spring, the opposite ends of said shaft and spring being free for relative movement, said spring being resiliently expansible lengthwise of said shaft, and anchoring means attached to the free end of said spring.

6. A fuse link flipout device for use in an expulsion type fuse tube, said device comprising a tubular elongated flexible shaft consisting of a close-wound wire helix, a helical tension spring telescopically related to and encircling said shaft, an adapter securing one end of said shaft to a corresponding end of said spring, the opposite ends of said shaft and spring being free for relative movement, said spring being resiliently expansible lengthwise and axially of said shaft, a nut attached to the free end of said spring, and a nut attached to the free end of said shaft, said nuts being engageable upon expansion of said spring to limit the extent of relative movement of said free ends in one direction.

7. A fuse link flipout device for use in an expulsion type fuse tube, said device comprising a helical compression spring and a rigid tubular sleeve telescopically encircling said spring, one end of said sleeve being anchored to a corresponding end of said spring, the opposite ends of said spring and sleeve being free for relative movement, the free end of said sleeve being enlarged diametrically to serve as anchor means.

8. A fuse link flipout device for use in an expulsion type fuse tube, said device comprising a helical compression spring, a rigid tubular sleeve telescopically encircling said spring, one end of said tube being anchored to a corresponding end of said spring and the other end being frustoconically flanged exteriorly and free for movement relative to said spring.

9. In combination with a fuse including a fuse tube open at one end, a pair of terminals one terminal being adjacent said open end, and a fuse link in said tube connecting said terminal and having a portion projecting from said end and anchored to said one terminal; of a flipout device removably positioned in said tube comprising outer and inner telescopically related tubular

members disposed in the open end of said tube, the ends of said members most remote from said open end being anchored together, at least one of said members including a spring and being expansible axially of the other member, the inner member providing an axial bore through which said fuse link extends, and the outer member having anchoring means engaging the open end of said tube, said fuse link normally holding said spring under stress, whereby upon rupture of said link it will be expelled from said tube.

10. In combination with a fuse including a fuse tube open at one end, a pair of terminals one terminal being adjacent said open end, and a fuse link in said tube connecting said terminal and having a portion projecting from said open end and anchored to said one terminal; of a flipout device removably positioned on said tube comprising a tubular member and a helical spring member which are telescopically related and disposed in the open end of said tube, the ends of said members most remote from said open end being anchored together, the opposite ends of said members being free for relative movement, the inner member of said device having an axial bore through which said fuse link extends, and the outer member having anchoring means engaging the open end of said tube, said fuse link normally holding said spring under stress, whereby upon rupture of said link it will be expelled from said tube.

11. In combination with a fuse including a fuse tube open at one end, a pair of terminals one terminal being adjacent said open end, and a fuse link connecting said terminals and having a portion anchored to said one terminal; of a flipout device removably positioned in said tube comprising a tubular elongated flexible shaft loosely embracing said fuse link, a helical tension spring telescopically and coaxially related to said shaft, an adapter securing one end of said shaft to a corresponding end of said spring, the opposite corresponding ends of said shaft and spring being relatively movable, and an anchoring nut on the relatively movable end of said spring engaging the open end of said tube, said spring being expanded lengthwise and axially of said shaft and normally maintained expanded by said fuse link acting through said shaft.

12. In combination with a fuse including a fuse tube open at one end, a pair of terminals one terminal being adjacent said open end, and a fuse link connecting said terminals and having a portion anchored to said one terminal; of a flipout device removably positioned in the open end of said tube and comprising a helical compressing spring loosely embracing said fuse link, and a rigid tubular sleeve telescopically encircling said spring, the end of said sleeve most remote from said open end being anchored to the corresponding end of said spring, the other end of said sleeve being enlarged diametrically and engaged with the open end of said tube, said spring being normally held under compression by said link and sleeve.

13. In combination with a fuse including a fuse tube open at one end, a pair of terminals one terminal being adjacent said open end, and a fuse link in said tube connecting said terminals and anchored to said one terminal; of a flipout device removably positioned in said tube comprising a helical compression spring loosely surrounding said fuse link, a rigid tubular sleeve telescopically encircling said spring, the end of said sleeve most remote from said open end being

anchored to the corresponding end of said spring and the other end being frusto-conically flared diametrically toward the corresponding end of said spring, said flared end engaging said open end of said tube, and a frusto-conically flared ferrule secured to said spring, said fuse link normally holding said ferrule nested in said flared end of said sleeve and said spring under compression.

14. In combination with a fuse including a fuse tube open at one end, a pair of terminals one of which is adjacent said open end, and a fuse link in said tube connecting said terminals and anchored to said one terminal; of a flipout device removably positioned in said tube comprising a tubular elongated flexible shaft consisting

5 of a close-wound wire helix loosely embracing said fuse link, a helical expansion tension spring telescopically encircling said helix and having its end most remote from said open end anchored to the corresponding end of said helix, the other ends of said helix and spring being relatively movable, an anchoring nut mounted on said other end of said spring engaged with said open end of said tube, and a second nut mounted on said other end of said helix and engageable with said anchoring nut for limiting the extent to which said spring may be expanded, said fuse link normally acting through said helix to hold said spring expanded.
